UNITED STATES PATENT OFFICE

CARL F. WOLTERS AND CHARLES SHULTE, OF MARIETTA, OHIO, ASSIGNEES TO REMINGTON RAND INC., OF BUFFALO, NEW YORK

PROTECTOR DEVICE FOR SAFES

Application filed April 18, 1928. Serial No. 271,054.

This invention relates to protector devices for safes, vault doors, and the like. The objects of this invention are the production of a reliably operable gas generating and gas emitting protector device for a safe or the like; the provision of means for causing said device to function when vibrations are set up as by an attempt to gain access to the safe or to the device itself by drilling, chiseling and other operations that may be employed in fracturing or opening the safe; the provision of means for causing the device to operate when an attempt is made to gain access to the interior of said device as by forming an opening therein by burning away a portion of the metal; the provision of means for causing the device to function when an attempt is made to cut off the hinges by a gas flame or the like; the provision of means for causing the device to function when an attempt is made to disable the mechanism of the device by pouring paraffin or any other liquid into the device; the provision of means for supporting the device in a position where it does not interfere with the ordinary use of the safe; the provision of means for locking the device in position on a door of the safe when the door is closed and to simultaneously set mechanism to permit the device to function when an attempt is made to gain access to the safe or the device itself by any means such as mentioned in the preceding objects; and the provision of means for locking the control mechanism automatically as the device is unlocked from the safe prior to moving it into non-functioning position.

Additional objects will be apparent from the following description taken in connection with the accompanying drawings in which,

Fig. 1 is a perspective view of the safe with the device swung into and secured in functioning position, portions of the safe being broken away to show its construction.

Fig. 2 shows the device resting on top of the safe in a non-functioning position.

Fig. 3 is a vertical longitudinal section through the casing of the device showing the mechanism conditioned to be operated.

Fig. 4 is a front view of the casing with a

portion of the casing broken away and the mechanism locked in disabled condition.

Fig. 5 is a vertical transverse section on the line 5—5, Figure 3, showing the mechanism conditioned for operation as in Figure 3. 55

Fig. 6 is an end elevation showing a portion of the casing broken away and the interior mechanism conditioned for non-operation as in Figure 4.

Fig. 7 is a front view of the gas canister. 60

Fig. 8 is an edge view of the gas canister.

Fig. 9 is a longitudinal section through the right hand hinge in Figure 3.

Fig. 10 shows a modification of the firing hammer construction in the normal set position. 65

Fig. 11 is a view similar to Figure 10 with the primary firing hammer in operated position.

Fig. 12 is a cross section on the line 12—12 70 of Figure 10 as viewed in the direction indicated by the arrows.

The protector device is shown in Figure 1 in its functioning position swung in front of the primary or right hand door of the safe. 75 The safe shown is of a well known type comprising a body of reinforced heat resisting composition, an outer shell of steel, and doors comprising inner and outer shells of steel enclosing a slab of heat resisting material. The right hand door carries the locking mechanism for the safe and through the usual overlapping rabbet construction prevents opening of the left hand door as is well understood. 80

The protector device is enclosed in a casing 85 20, (Figs. 1 to 6), comprising a flanged front male member 21 and a flanged rear female member 22, the flanges of which overlap and are secured together at the top by any suitable means and are spaced along the sides and bottom as shown at 23, (Figs. 3, 4, 5 and 6). The flange of the front male member is provided with ports 24, (Figures 5 and 6), to provide a passage for gas from the interior of the casing to the space 23 between the flanges of said members which communicates with the outside of the casing. 90

The casing is preferably connected by hinges 25 to the top of the safe to permit it to occupy either of the positions shown in Figs. 1 and 100

2. Each hinge comprises a member 26 secured to the top of the safe. This member is provided with a groove 27, (Fig. 9), extending from the hinge end of the member 5 to a point near its other end to receive a short length of fuse 28. Only one hinge is provided with a fuse as both hinges must be cut before the device can be detached. However, 10 both hinges are shown of the same construction. When this member is secured in position on the safe, it prevents unauthorized removal of the fuse. The other hinge member 29 has a right angular end 30, (Figs. 3, 4 and 5), extending through a slot into the upper 15 portion of the flange of the front member 21 of the casing, with the right angular portion in contact with and secured to the inside of said flange by any suitable means. This interlocking connection between this hinge member 20 and the casing prevents removal of the hinge member from the casing when the casing is locked to the safe by means later described, even when the rivet connections or the like between these parts have been cut or 25 removed.

Secured to the back of this hinge member 29 is a trough shaped member 31, (Figs. 4, 5, 6 and 9), forming with the hinge member a housing for the end of a fuse 32, (Figs. 3 and 9), extending into the interior of the casing. One end of the fuse as shown in Figure 9 is in close proximity to the end of fuse 28. The lower end of the member 31 extends into the flange of the front member 21 of the casing 35 as indicated in Figure 5. The hinge member 29 and trough shaped member 31 are preferably welded together or otherwise secured or integrally formed and together have a close fitting connection with the flange of the front 40 member of the casing. A block 33, (Figs. 2 and 5), limits the movement of the casing toward the safe. The top of the safe may be provided with a rest 34, (Figs. 1 and 2), and the casing with a cooperating member 35.

45 Secured in spaced relation to the rear member of the casing by an upper angle member 38, (Figs. 3, 7 and 8), and a lower angle member 39 is a canister 40 of the general configuration shown in these figures. The horizontal portion of the upper angle member 38 preferably extends through a slot in the rear wall of the canister into contact with the inner face of the upper wall of the canister to which it is secured by any suitable means 55 which by this construction is relieved of the weight of the canister.

The lower inclined edge of the canister is provided with a filling opening 41, (Fig. 7), suitably closed after the canister is filled by 60 a plate 42 soldered in place.

In the right hand end and near the top of the canister is secured a primer cap 43, (Figs. 3, 5, 7 and 8). This cap extends into a layer of tear gas producing compound 45 lying over 65 a large quantity of a smoke producing com-

70 pound 46 filling the larger portion of the canister to a point indicated by the dash line 47, (Figs. 7 and 8).

The gas generated is emitted through openings 48, (Figs. 3 and 7), covered by collodion or other like substance which preferably is 75 also employed to seal around the primer cap 43.

The canister is preferably constructed of 80 zinc, which under the heat generated by the smoke producing compound, melts to permit the rapid discharge of smoke gas from the canister. The gases generated are discharged from the casing through the ports 24, (Figs. 85 5 and 6), and space 23 hereinbefore described.

The primer cap 43 is set off by a firing hammer 50, (Figs. 3 to 6), suitably pivoted at 51 to a stud on a bar 54. The hammer is actuated by a spring 52 bearing against a shoulder on the hammer and a shoulder formed by a horizontal flange 53 on the forwardly extending portion of the vertically extending bar 54 which is generally L-shaped in cross-section with the base of the L secured 90 to the rear member of the casing and constituting a guide for a slide 55, later more fully described. The forwardly extending member rests against a side edge of the canister and supports it, and its front edge is 95 cut away providing upper and lower projections 56 and 57 abutting against a member 58, (Figs. 3 and 5), secured to the inner face of the front member of the casing. The function of member 58 and the flange 53 will 100 be described later.

The hammer is normally held in its cocked position by a flat spring 60, (Figs. 3 to 6), suitably secured to a post supported on the rear member of the casing and constructed 105 to constantly tend to move to release the hammer. The spring 60, (Figs. 3 to 6), is prevented from releasing the hammer by a tiltable rod or initiating device 61 bearing on the flange 53, before described, and on a stud 62 secured to the spring 60. The ends of the rod 61 are rounded or pointed to make its operation sensitive to small vibrations as is understood. When the rod 61 is free, vibrations set up in the safe or the protector device 110 will cause it to tilt to permit the spring 60 to release the firing hammer.

For the purpose of preventing tilting of said rod when the safe door is opened and the device is not in the functioning position shown in Figure 1, and to prevent functioning after it is moved out of the position shown in Figure 1, disabling means is provided. Secured to or integral with the rod 61 is a collar 63 preferably circular in shape, with 115 which cooperates an apertured holding member 64 secured to the slide 55, the aperture in the holding member being of the same shape as the collar 63 and just slightly larger. This holding member when in the position 120

shown in Figures 4 and 6, prevents tilting of the rod 61. This is the position it occupies when the device is disconnected from the door of the safe as later described. When the holding member is in the position shown in Figures 3 and 5, the rod is free to be operated.

The slide 55, (Figs. 3 to 6), which carries the holding member 64 is provided with upper and lower bolts 65 operating in slots in the rear member of the casing. Connected to the outer end of the lower bolt 65 is a U-shaped locking member 66, (Figs. 5 and 6), cooperating with a locking finger 67 projecting from a block 68 secured to the right hand door of the safe. These parts are shown in locking position in Figure 5 and in unlocking position in Figure 6. Depending downwardly from locking member 66 is a manipulative member 69, the end of which may be a flattened portion to bear any suitable indication to show the condition of the device when the flattened portion is lowered from the position in Figure 3 to the position in Figure 4 where it may be readily viewed.

When the tiltable rod 61 is disabled as in Figure 6, the slide 55 is held in its lower position by a plunger bolt 70 operating in a sleeve 71 threaded in the slide and pressed inwardly by a spring 72 mounted in holding member 64. The plunger 70 is pressed back to release the slide to permit locking the casing to the safe and conditioning the rod 61 for operation, by a pin 73 secured to right hand door 35 of the safe. As seen in Figure 6, the parts shown therein may be moved into the position shown in Figure 5.

The slide 55 may be locked into its moved position shown in Figs. 3 and 5 by a dial controlled lock 74 as indicated generally in Figs. 1, 3 and 4. The lock bolt 74' of the lock is shown thrown in Figures 3 and 5.

The fuse 32, Figure 3, extends into close proximity with the front wall of the front member of the casing and is preferably laid substantially as indicated in Figures 3 and 5, extending from the hinge 29 through the casing and downwardly to the notches in the projections 56 and 57 of the bar 54, and leading into the top wall of the canister into the charge of tear gas compound 45, Figure 7.

To prevent fouling of the protector device by the pouring into the casing of liquids such as water, melted paraffin, etc., a float 75, Figures 3 and 4, is provided. This float is supported on one end of a wire bent at 76 as shown in Figures 3 to 5 to tilt the tiltable bolt 61 when lifted by a liquid poured in the casing. The other end of the wire is anchored for pivotal movement at 77 in the bar 54 as indicated in Figures 3 to 5.

The casing members are preferably constructed of soft steel. The member 58, before referred to, is constructed of hard steel and is secured to the front casing member at

spaced points. If an attempt is made to drill a hole through the front casing member, the drill on contacting with the member 58 will, because of the character of material of this member and the means of securing it, cause it to set up vibrations to cause the member 61 to tilt. As shown the flanges of the member 58 are shorter than the flanges of the front member of the casing, to freely permit vibration of the member 58 and to permit the passage of gas to the ports 24.

The slide 55 carries a pin 78, (Figs. 3, 4, and 5), which rocks the firing hammer 50 clockwise as the slide is lowered. This changes the tension of the spring 52 and prevents the spring from becoming set.

In order to minimize spring failure and to gain higher efficiency, it may be desirable to provide a dual priming system such as shown in Figures 10, 11 and 12. In addition to the primary hammer 50 and its spring 51 which are in all respects the same as the correspondingly designated hammer and spring in Figs. 4 and 5, there is provided a secondary hammer 150 and spring 151 and an additional primer cap 143. The primary and secondary parts are mounted symmetrically with respect to the canister 40 as shown in Figure 12.

As shown in Figure 10 the primary hammer 50 is provided with a laterally extending pin 152 bearing against the tail of the hammer 150 to normally prevent it from firing before the primary hammer 50 has been released by the parts 67 and 60. As shown the spring 151 bears on the secondary hammer 100 in the direction of its pivot so that normally it does not urge the hammer in the firing direction. This is shown also in Figure 11, in which the secondary hammer is still in its cocked position at the time the primary hammer contacts with its primer cap. At this instant, the vibration set up by the first hammer striking its primer cap is sufficient to cause the secondary hammer to overcome the frictional resistance on its pivot and to move 105 it across its dead center, when its spring will impel it against its primer cap thus causing firing of the secondary primer cap shortly after the primary cap has been fired. This firing in rapid succession of the two primer caps will give better initial combustion to 110 the gas charge. This dual arrangement obviously possesses another distinct advantage 115 as it greatly reduces the chance of misfire from defective primers.

Various changes in structure can be made within the scope of the claims without departing from the spirit of the invention.

What is claimed is:

1. In combination with a safe provided with a swinging door, a protector device, means movably connecting the device to the safe to permit the device to be swung upon the top of the safe when the door is to be opened and to be swung against the door 130

- when the door is closed and means for controlling the operation of the protector device.
2. In combination with a safe provided with a door to permit access to the interior of the safe, a protector device normally conditioned for non-operation, means movably supporting said device on the body of the safe to permit the device to be swung into the path of said door when closed, means operable as the protector device is moved against the door to permit the device to be conditioned for operation, and means for conditioning said device for operation.
3. In combination with a safe, a protector device secured to the safe, means operable by vibrations set up in the device for causing said device to function, a casing for said device, and a lining for said casing operable to produce vibrations to cause said device to function as the lining is encountered in an attempt to pierce said casing.
4. A protector device for safes comprising a gas generating means, a casing therefor comprising overlapping parallelly spaced inner and outer flanges, the inner one of which has an opening effecting communication between the interior of the casing and the space between said flanges.
5. In a protector device comprising a gas generating means, and a casing therefor comprising members having oppositely directed spaced flanges facing each other with the flange of one abutting against the body portion of the other and provided with openings communicating with the interior of the safe and the space between the flanges.
6. A casing for a gas generating device comprising a plurality of male and female members provided with overlapping flanges, portions of which are in contact and other portions of which are out of contact to provide a space, the male member being provided with an opening establishing communication between said space and the interior of the casing.
7. In a protector device comprising a casing and a gas generating means within the casing, a hollow hinge for supporting said casing upon a device to be protected, and a fuse extending through the hole in said hinge and having portions thereof extending substantially in contact with a wall of said casing and another portion connected to said gas generating means.
8. In a protector device comprising a casing and gas generating means within the casing, a hinge secured thereto having a channel extending from a point close to one end of one of the hinge members through said hinge members and opening into the casing, and a fuse located in said channel and extending into said casing and about one of its sides and into cooperative relation with said gas generating means.
9. In a protector device including a spring actuated firing hammer, movable means for holding said device in position on an article to be protected, and means for changing the tension of said spring upon movement of said holding means.
10. In a protector device, a firing hammer, a trip for said hammer releasable by vibrations set up, means for supporting said device upon an article to be protected in a position where it is intended to function and in another position where it is not intended to function, and means for disabling said strip when the device is in a non-functioning position.
11. In a protector device, a firing hammer, a trip for said hammer releasable by vibrations set up, means for supporting said device upon an article to be protected in a position where it is intended to function and in another position where it is not intended to function, means for locking said device in a functioning position, and means controlled by said locking means for disabling said trip when moved into unlocking position.
12. In a protector device comprising a firing hammer, a spring for actuating the hammer, movable means for releasing said hammer, a second movable means for causing said first movable means to function, and means movable into position for holding said second movable means or permitting it to move.
13. In a protector device comprising a firing hammer, a spring for actuating the hammer, movable means for releasing said hammer, a second movable means for causing said first movable means to function, and means movable into position for holding said second movable means or permitting it to move, locking means for locking said device upon an article to be protected, and means operable by movement of said locking means into locking position to position said holding means to disable said second mentioned means.
14. In a protector device comprising means to set it into operation, and a controlling means therefor including a trigger operable to release said device for operation, a member for engaging and preventing operation of said trigger having an enlarged portion for tilting said member to release said trigger, and means movable over said enlarged portion to prevent said member from tilting.
15. In a protector device having means controlling the operation thereof comprising an elongated initiating member set on end and tiltable to release said device for operation, a collar thereon, and a member movable over said collar to hold said initiating member against tilting.
16. In a protector device, the combination of a primary firing hammer, and a secondary firing hammer normally restrained against firing by the primary hammer.

17. In a protector device, the combination of a primary firing hammer, means for causing the hammer to move toward firing position by vibrations set up in the device, a secondary hammer, and means for causing it to fire by vibrations set up by the firing action of the primary hammer.
18. In a protector device, the combination of a primary firing hammer, a spring normally bearing on said hammer for causing the hammer to move toward firing position, a secondary firing hammer, and a spring normally bearing on it in the direction of its pivot.
19. In a protector device, the combination of a primary firing hammer, a spring normally bearing on said hammer for causing the hammer to move toward firing position, a secondary firing hammer, means on the primary hammer normally preventing a firing movement of the secondary hammer, and a spring normally bearing on it in the direction of its pivot.
